UNITED STATES PATENT OFFICE.

JOHN A. FERGUSON, OF DENVER, COLORADO, ASSIGNOR TO THE FERGUSON-SYNSTONE CO., OF DENVER, COLORADO.

WALL CONSTRUCTION.

1,248,837.

Specification of Letters Patent. Patented Dec. 4, 1917.

Application filed May 23, 1916. Serial No. 99,444.

To all whom it may concern:

Be it known that I, JOHN A. FERGUSON, a citizen of the United States, residing at Denver, in the county of Denver and State 5 of Colorado, have invented certain new and useful Improvements in Wall Constructions, of which the following is a specification.

This invention relates to certain new and useful improvements in wall constructions 10 and it has for its objects among others to provide a simple and efficient hollow wall construction in which the blocks and facing or veneer, whether applied interiorly or exteriorly shall be firmly joined together, the 15 improvement being specially applicable to silos and other constructions involving a cylindrical wall, in which the bases of the building blocks and the veneering slabs are devoid of curvature, but are laid in courses, 20 substantially alining with the curvature or arc of the wall.

The blocks are of novel formation and the facing or veneer is so secured thereto that the whole constitutes a self-bracing reliable 25 wall which may or may not be reinforced as conditions may require.

Other objects and advantages of the invention will hereinafter appear and the novel features thereof will be particularly 30 pointed out in the appended claim.

The invention is capable of embodiment in a variety of forms, those herein illustrated being what I consider at the present time best adapted to the purposes and ends in 35 view.

Referring to the accompanying drawings, in which the invention is clearly illustrated in its preferred forms,

Figure 1 is a perspective view showing a 40 portion of a silo, the walls of which are constructed in accordance with my present invention.

Fig. 2 is an enlarged top plan with portions broken away.

Fig. 3 is an enlarged perspective view of 45 one of the blocks, showing a reinforcing wire and anchors for the veneer or facing.

Fig. 4 is an enlarged perspective view of one of the facing or veneer members.

Fig. 5 is a top plan, showing the embodiment 50 of the invention in a wall in which the facing or veneer is upon the inner face,

Fig. 6 is an enlarged perspective view looking from above, showing the facing secured to a block.

55

Fig. 7 is a top plan, showing the embodiment of the present invention in a straight wall.

Fig. 8 is an enlarged perspective detail, looking from above, showing one form of 60 block with a reinforcing rod and anchors for the veneer or facing in position.

Fig. 9 is a fragmentary perspective detail, showing two adjacent courses of the 65 blocks.

65

Like numerals of reference indicate like parts throughout the several views.

In carrying out my invention, I may employ blocks of different forms, and in some instances provided with a greater or less 70 number of webs or lateral projections. These blocks are of suitable composition, properly formed and, in the present instance, I have chosen to show such blocks as formed with two projections or webs each. 75 The base or main body portion of the blocks 1 is shown as being provided with laterally disposed spacing webs 2 and 3, but, whether or not one or more spacing webs are employed on each block, the spacing web 3 is 80 in all instances a terminal or end web. The size and cross sectional formation of these webs or projections may vary. In the present instance, I have shown them tapered, but it is to be understood that this is not 85 a necessary feature of the construction.

The terminal web 3 is so formed at one end of the base portion of the block that its butt portion partly projects beyond the adjacent end edge face of its base and forms 90 therewith an open angled corner, between said end edge face and the abutting projecting part of said spacing web, providing a vertical rabbet or recessed shoulder 4 for seating the opposite end 5 of a similar adjacently laid block. When the facing or

95 veneer is employed upon the inner face of the wall, as seen in Figs. 5 and 6, the blocks 1 are provided with the rabbet 4, the same as in the form shown in Fig. 8, and the outer face of the block adjacent said rabbet is

100 slightly beveled, as seen at 6, so as to avoid projections and to provide a continuous practically curved outer face to the wall,

as will be readily understood upon reference to Fig. 5.

In practice, the blocks are laid in the wall in the usual manner and in the form shown in Figs. 1 and 2 where the facing or veneer 7 is applied to the exterior of the wall, the outer face surfaces of which facing blocks 7 are suitably beveled at one end, as seen at 8, Fig. 4, and are placed in position, as seen in Figs. 1 and 2, so that each facing block 7 substantially opens the webs of one of the blocks 1 and the adjacent web of the adjacent block. The end of these facing members 7, distant from the beveled portion 8, may be provided with a beveled lip or ledge 11, formed by a slight extension of the inner base portion beyond the end edge face thereof, as shown in Figs. 2 and 4. In practice, the facing blocks 7 are disposed so as to avoid direct contact with the webs 2, so as to leave a slight air space between the facing blocks and the adjacent faces of the webs, as seen at 9 in Fig. 2, the blocks 1 and the facing or veneer blocks 7 being bound together in any suitable or well-known way, such, for instance, as bonding ties or anchors 10 of metal, shown in Fig. 2, laid in the mortar joints, or otherwise, as may be found most expedient. When these bonds or ties are applied, as shown in Fig. 2, a single bond or tie serves to secure the adjacent ends of two adjacent facing or veneer blocks.

It will be readily understood that when it is not desired to make the inner or outer face of the wall of a veneer or facing, such as shown in Fig. 2, but to employ in lieu thereof plaster-board or metal or wooden lath and plaster-board or other finish, the laths or the plaster-board may be secured directly to the webs 2 of the blocks in any of the well-known ways, such, for instance, as by ties or bonds of wire, it being understood that the present invention resides primarily in the structural disposition of the terminal or end web 3 relatively to the base of its block, and the employment of such blocks in a construction of wall *per se*, wherein the lateral spacing webs do not interengage or interlock with complementary projections of the veneering wall or its equivalent.

The wall constructed as hereinbefore described and as shown in Figs. 1 and 2, has the end 5 of one block seated in the angular rabbet or recess 4 of the adjacent block which, as will be seen upon reference to Figs. 2 and 5, provides a dove-tail or wedging effect, and when composition facing or veneer blocks 7 are employed they may preferably interengage at their ends, as seen at 11, thus forming a most rigid construction. The facing may be upon the inner or the outer face of the wall, whether this facing

be of composition veneer blocks 7 or of plaster-board, corrugated metal, sheathing, lath and plaster, brick, tile or any other preferred material. In Figs. 5 and 6 I have shown the facing 12 as applied to the inner face of the wall, the facing being bonded to the webs by suitable bonds 10.

I may sometimes employ a reinforce, as 13, of any suitable nature supported upon the webs 2 and 3, as shown in Figs. 3, 6 and 8, and built into the wall as the courses thereof are laid.

The essential features of the invention as above described may be embodied in a straight wall as well as in one which is curved and such is shown in Fig. 7 wherein the blocks 14 have the webs 15, substantially the same as the webs 2 and 3, respectively, and the rabbets or vertical recesses 16, formed by the projecting part of the butt portion of the terminal web 15, to receive the adjacent ends 17 of adjacent blocks. In this form the inner or outer facing 18 of the wall may be of plaster-board, composition veneer, or any other suitable material applied in any desirable manner.

The bonds or ties 10 may or may not be applied to each web of all of the blocks, according to the character of the wall to be built.

Upon reference to Fig. 9, it will be seen that in laying the courses the blocks 1 are reversed upon each alternate course so that the end web of the one block in the one course will be beneath the end 5 of the next course above, and so on throughout the structure. This effects a better bonding of the blocks, as will be readily understood upon reference to Fig. 9.

The wall formed of the blocks 1 with their interlocking engagement at the ends thereof may be made double or triple in thickness as may be desired, the body portions of the blocks 1 being arranged contiguous to the end faces of the webs, and then the outer facing of veneer 7 or other material applied to the webs of the outermost or innermost blocks, according to whether the facing is applied upon the outside or inside of the wall.

Modifications in details, proportion of parts etc., may be resorted to without departing from the spirit of the invention or sacrificing any of its advantages.

What is claimed as new is:—

In substantially cylindrical hollow wall construction, a curving wall section built up in courses of building blocks, having a base portion, devoid of curvature, the ends of which are slightly beveled, and one end being provided with a lateral terminal web, forming at its joinder therewith an acute angular corner recess to seat the opposite beveled end of an adjacently laid block in

wedged relation; a contiguously laid wall section of plane surfaced slabs, devoid of lateral interlocking projections, said slabs being so laid in courses as to span the length of the opposed building blocks, with their joints abutting said lateral webs; interengaging means being provided at opposite

ends of said slabs to allow of a smooth surface joinder therebetween; and bonding means tying the joined ends of said slabs 10 directly to their abutting block terminal web, substantially as described.

In testimony whereof I affix my signature.
JOHN A. FERGUSON.
